UNITED STATES PATENT OFFICE.

CARL J. LJUNGGREN, OF PROVIDENCE, RHODE ISLAND.

HYGIENIC CHALICE.

1,118,364.

Specification of Letters Patent. Patented Nov. 24, 1914.

Original application filed January 23, 1907, Serial No. 353,725. Divided and this application filed October 10, 1908. Serial No. 457,158.

To all whom it may concern:

Be it known that I, CARL JULIUS LJUNGGREN, a subject of the King of Sweden, residing at Providence, in the county of Providence and State of Rhode Island, have invented certain new and useful Improvements in Hygienic Chalices, of which the following is a specification.

My invention relates to an improvement 10 in chalices, and the object is to provide means whereby an outlet chamber and reservoir are so constructed that the assemblage of the parts is simple and consists of very few parts.

15 This application is a division of my application filed January 23, 1907, Serial No. 353,725 on improved hygienic communion chalices.

The invention consists of certain novel 20 features of construction and combinations of parts which will be hereinafter described and pointed out in the claims.

In the accompanying drawing I have shown a portion of the invention in a vertical section.

A represents the chalice or cup and 1 is the leg which is hollow, upon which the chalice is mounted. A flange 2 extends inwardly and downwardly from the drinking 30 edge of the cup, and received within the cup and extending above the lower depending edge of the flange is a reservoir 3. The reservoir is supported in the chalice by a tubular extension 4, which is formed on the 35 bottom of the reservoir and received in the leg 1 of the cup. The reservoir is so supported within the chalice that a space is formed between the chalice and the reservoir for the waste liquid, which is adapted 40 to pass through openings 5 into the tubular extension and then down into the leg 1.

A cover 6 is mounted on the reservoir and is preferably made hollow or sunken inwardly nearly cup-shape forming an outlet 45 chamber. An opening 7 is formed in the bottom of the cover, and connected to the cover is an inlet chamber 8, which is in communication with the outlet chamber through the opening 7. The inlet chamber extends upwardly between the cover and wall of the reservoir so as to receive the liquid from the reservoir when the cup is tilted for conducting the liquid to the outlet chamber. A ball valve 9 is received in 55 the inlet chamber for regulating the flow

or discharge of liquid from the inlet chamber to the outlet chamber, the valve regulating the amount of liquid which is discharged from the inlet chamber to the outlet chamber in measured quantities. An 60 air-vent 10 is formed in the wall of the reservoir along the upper edge.

When the chalice is tilted the liquid from the reservoir 3 will enter the inlet chamber 8 and when the chalice is moved to an upright position a certain quantity of the liquid will pass from the inlet chamber on to the cover or into the outlet chamber 6. The liquid is discharged from the outlet chamber on to the flange 2. The liquid 70 which is not consumed and which has been discharged from the outlet chamber on to the flange 2, will pass down between the reservoir and cup and finally pass through the openings 5 in the tubular extension 4 75 down into the leg of the chalice.

From the foregoing it will be seen that I have provided a chalice in which the reservoir forms a receptacle for the liquid as well as an outlet chamber, by having the 80 cover made into the proper shape to form a receptacle to receive the liquid as it is discharged from the reservoir. This makes a very simple construction which can be manufactured at a small cost.

It is evident that more or less slight changes might be resorted to in the form and arrangement of the several parts described without departing from the spirit and scope of my invention, and hence I do 85 not wish to be limited to the exact construction herein set forth, but:

Having fully described my invention, what I claim as new and desire to secure by Letters Patent, is:

1. A chalice comprising a cup, a reservoir supported within the cup, whereby space is formed between the outer wall of the reservoir and the inner wall of the cup, a concave cover mounted upon the reservoir for forming an outlet chamber for receiving a measured quantity of liquid, and means located in the reservoir for discharging a measured quantity of the liquid to the outlet chamber when the cup is being moved 100 to an upright position.

2. A chalice comprising a cup, a reservoir mounted in the cup whereby space is formed between the outer wall of the reservoir and the inner wall of the cup, a concave cover 105

mounted upon the reservoir forming an outlet chamber, an inlet chamber received in the reservoir, and connected to the outlet chamber, said outlet chamber having an opening therein for forming a communication between the inlet chamber and outlet chamber, said inlet chamber adapted to be filled with the contents of the reservoir when the cup is in a tilted position, and the liquid entering the inlet chamber being discharged into the outlet chamber only when the cup is moved to an upright position.

3. A chalice comprising a cup having a flange extending downwardly from the drinking edge thereof, a reservoir supported in the cup, a space formed between the inner wall of the cup and the reservoir, said reservoir extending above the lower edge of the flange, a concave cover mounted upon the reservoir forming an outlet chamber, means received in the reservoir connected to the outlet chamber for conducting liquid to the outlet chamber when the cup is brought from an inclined position to an upright position, said flange acting as a baffle to prevent the liquid which has passed on over the lower edge of the flange from returning and passing onto the flange.

4. A chalice comprising a cup, a reservoir supported within the cup, a concave cover mounted upon the reservoir for forming an outlet chamber for receiving a measured quantity of liquid, and means located in the reservoir for discharging a measured quantity of the liquid to the outlet chamber when the cup is in an upright position and after the cup has been brought from a tilted position.

5. A chalice comprising a cup having a flange extending downwardly from the drinking edge thereof, a reservoir supported in the cup, said reservoir extending above the lower edge of the flange, a concave cover mounted upon the reservoir forming an outlet chamber, means received in the reservoir connected to the outlet chamber for conducting a measured quantity of liquid to the outlet chamber when the cup is brought from an inclined position to an upright position, said cup and reservoir having a space formed there-between for receiving the drippings and waste liquid from the flange, said flange acting as a baffle to prevent the liquid, which is passed over the lower edge of the flange, from returning and passing upon the flange.

6. A chalice comprising a cup, a reservoir supported within the cup, a concave cover mounted upon the reservoir for forming an outlet chamber for receiving a measured quantity of liquid, means located in the reservoir for discharging a measured quantity

of the liquid to the outlet chamber when the cup is in an upright position and after the cup has been brought from a tilted position, 65 and an automatic valve located in said means for regulating the flow of liquid therethrough.

7. A chalice comprising a cup, a reservoir supported in the cup and having a cover 70 mounted upon the reservoir for forming an outlet chamber, an inlet chamber located within the reservoir and supported by and in connection with the outlet chamber, said inlet chamber adapted to discharge a measured quantity of liquid from the reservoir to the outlet chamber when the cup is being brought to an upright position and from a tilted position.

8. A chalice comprising a cup, a reservoir supported in the cup and having a cover mounted upon the reservoir for forming an outlet chamber, an inlet chamber located within the reservoir and supported by and in connection with the outlet chamber, said inlet chamber adapted to discharge a measured quantity of liquid from the reservoir to the outlet chamber when the cup is being brought to an upright position and from a tilted position, said outlet chamber adapted 90 to discharge the contents thereof at the drinking edge of the cup.

9. A chalice comprising a cup, a reservoir supported within the cup, a concave cover mounted upon the reservoir for forming an outlet chamber for receiving a measured quantity of liquid, and means located in the reservoir for automatically discharging a measured quantity of the liquid to the outlet chamber.

10. A chalice comprising a cup, a reservoir supported within the cup, whereby space is formed between the outer wall of the reservoir and the inner wall of the cup, a concave cover mounted upon the reservoir for forming an outlet chamber for receiving a measured quantity of liquid, and means located in the reservoir for discharging a measured quantity of the liquid to the outlet chamber when the cup is in an upright position, and after the cup has been brought from a tilted position, said means being adapted to prevent the discharge of liquid to the outlet chamber when the cup is brought from an upright position to a tilted position, and as long as the cup remains in a tilted position.

In testimony whereof I affix my signature, in the presence of two witnesses.

CARL J. LJUNGGREN.
